UNITED STATES PATENT OFFICE.

SAMUEL S. FINESILVER, OF CLEVELAND, OHIO.

LIGHTING OUTFIT FOR PHOTOGRAPHIC WORK.

Application filed July 27, 1923. Serial No. 654,144.

To all whom it may concern:

Be it known that I, SAMUEL S. FINE-
SILVER, a citizen of the United States, residing
at Cleveland, in the county of Cuyahoga
5 and State of Ohio, have invented certain
new and useful Improvements in Lighting
Outfits for Photographic Work, of which
the following is a specification.

This invention relates to lighting outfits
10 particularly adapted and intended for
photographic work, for the purpose of
illuminating any object which is to be photo-
graphed. The device is portable and can be
used in a house or other place where an
15 electrical circuit is available.

The device includes a gang of lamps
mounted on a stand and adjustable to direct
the illumination to various angles or posi-
tions, and the device is foldable or collapsi-
20 ble so that it can be carried in a small space.
Various features of novelty will be ap-
parent from the following description and
the accompanying drawings in which Fig.
25 1 is a front view of a part of the cabinet.
Fig. 2 is an end view thereof. Fig. 3 is an
elevation of the cabinet with one side re-
moved and showing the bracket and stand
folded therein. Fig. 4 is a section on the
line 4—4 of Fig. 3. Fig. 5 is a cross-section
30 of the cabinet showing the adjustment of
one of the lamps. Fig. 6 is a partial rear
elevation, partly in section, of the outfit.
Fig. 7 is a detail of one of the supporting
arms of the stand.

35 The outfit may be supported by a tripod
stand having a central column consisting of
a telescopic section 6, which may be ad-
justed to any height desired, the lower sec-
tion having folding legs 7. The upper sec-
40 tion of the standard carries a pair of arms
each of which consists of an inner section 8
and an outer section 9 connected by hinged
elbow joint 10. The section 8 is pivoted to
a sliding collar 11 with hinged braces 12
45 permitting the arms to be folded to par-
allelism with the standard, the arms being
confined on the standard by a knob 13
screwed on the top thereof. The free ends
50 of the outer arm sections 9 are forked as
indicated at 14, to engage under a thumb
nut 15 engaging a screw 16 one of which is
fixed in each end of the casing.

This casing or box consists of a rectan-
gular frame 17 with a removable back 19,

and the frame is provided with a handle 20
whereby the whole outfit may be carried
when it is knocked down. The whole stand
may be folded to small compass and placed
within clips 22 in the upper part of the
cabinet as shown in Fig. 4.

55 The lamps 23, of which three are shown
mounted in the separate compartments in
the casing, in front of reflectors 24, the lamp
sockets being held by a bracket 25, which
also supports the reflector. Each lighting
60 unit, as thus described is separated by a
swinging bracket consisting of a pair of
plates 26 the opposite ends of which are
clamped by screws 27 against a ball 28 and
fixed to the bottom of the cabinet, and a
65 ball 29 fixed to the rear of the reflector
bracket. A handle 30 enables the light to
be manipulated or adjusted, this action be-
ing permitted by the ball connection at 28
and 29, so that the lamps can be swung in
70 and out and adjusted at various angles, as
illustrated in Fig. 5. A copper cord con-
nection 31 is provided for the lamps, and
may be tapped into any house socket or the
like. The pivotal connection at 16 between
75 the cabinet and the supporting arms enables
the cabinet as a whole to be turned in va-
rious directions, and it can also be rotated
on the standard 6.

The invention is not limited to the partic-
ular structures shown, but may be modified
in various ways.

I claim:

1. A portable lighting outfit comprising
a casing adapted for hand carriage and con-
taining a gang of lamps, the casing being
openable to expose the lamps, and a support-
ing folding stand adapted to be folded and
enclosed within the casing for transporta-
tion, said stand having a single supporting
90 column and oppositely extending arms pro-
jecting therefrom, each arm having a jointed
section at the outer end thereof, and means
to detachably connect the ends of said
jointed section to opposite ends of the cas-
ing, said means including pivots whereby
the casing may be adjusted to various angles.

95 2. A portable lighting outfit comprising
a casing, having an openable front, lamps
and reflectors supporting the same, and ad-
justable brackets fixed to the bottom of the
casing and supporting the reflectors and
lamps, said brackets each comprising a ball

fixed to the bottom of the casing, another ball fixed to the back of a reflector, and clamping plates engaging the balls, said brackets being adjustable to swing the lamps into or out of the casing and also to set the lamps at various angles with respect to the casing.

In testimony whereof, I affix my signature in presence of two witnesses.

SAMUEL S. FINESILVER.
Witnesses:

JOHN A. BOMMHARDT,
G. MOSENBERG.
